ANGULARITY INDICATOR FOR GRINDING CRANKSHAFTS

Paul F. Koebbe, Jackson, Mich.

Application April 4, 1945, Serial No. 586,589

4 Claims. (Cl. 51—239)

1

The present invention relates to improvements in centering and set-up gauge apparatus particularly adapted to crankshaft grinding equipment.

It is an object of the present invention to provide an improved centering and set-up gauge for crankshaft grinders in which an indicator gauge has been permanently associated with the work rest.

Another object is to provide an improved combination work rest and indicator.

A further object is to provide a combined work rest and indicator gauge for grinders especially adapted for centering and setting up crankshafts having the crank pins located at 90° or 120° to each other.

These and other objects and advantages residing in the combination, construction and arrangement of parts will be more fully understood from a consideration of the following specification and attached claims.

In the drawings,

Fig. 1 is a side elevational view illustrating my combination steady rest and indicator as viewed in side elevation in crankshaft grinding,

Fig. 2 is a fragmentary enlarged side elevational view of a portion of the construction shown in Fig. 1, with parts thereof shown in vertical cross section, and

Fig. 3 is a side elevational view of a modified form of shoe construction.

It is standard practice in the grinding of crankshaft bearings to chuck the same in such a position that it will rotate about the axis of the bearing being ground. Line bearings present little difficulty in setting-up and gauging. Connecting rod bearings present an entirely different problem, especially where the throws of the crank are disposed at 90° or 120° to each other. Employing standard methods, considerable time is consumed in setting-up and gauging in going from one connecting rod bearing to the next to assure each bearing is being ground on the proper axis of rotation.

The present invention has been carried out in connection with the work or back rest 10 adjustably supported through bolts 12 for axial movement along the table 14 of the crankshaft grinding machine. While the invention has been adapted to a "Landis" 22" x 72" regrounding machine, the principles are not thus limited in this application.

As shown in Fig. 1, the crank pin 16 of the crankshaft 18 is supported at its ends in the usual chuck (not shown) for rotating the pin 16 around its center. The grinding wheel 20 is ro-

2

tated in the direction indicated by the arrow. To steady the pin 16 against the action of the grinding wheel 20, shoes 22 and 24 define a back rest. The shoe 22 is carried upon an axially slideable plunger 26 while the shoe 24 is carried by a swinging jaw 28 pivoted upon a stud 30. A threaded stop 32 adjusted in and out through the knob 34 regulates the angularity of the jaw 28 and the location of the shoe 24.

Referring to Fig. 2, the plunger 26, which is freely slideable in the bore 36, has a flat axially extending spot 38 which is engageable by the nose of the thumb screw 40 to prevent rotation of the plunger 26 yet permitting axial movement. Co-axial with the bore 36 is a second bore 42 to receive a threaded bushing 44 held in position by the set screw 46. A threaded shaft 48 is adjustably threaded in the bushing 44 with one of its functions that of providing an adjustable abutment at 50 for the inner end 52 of the plunger 26. A knurled jam nut 54 locks the shaft 48 in all positions of adjustment of the abutment 50.

Threaded on the outer end 56 of the shaft 48 is an internally and externally threaded nut 58. An internally threaded housing 60 is carried on the nut 58 and axially adjusted by turning with the set screw 62 preventing relative rotation between the housing 60 and the nut 58 in desired positions of adjustment.

30 A dial indicator 64 of standard construction is shown mounted in the housing 60, being held in position by a set screw 66. The axially movable plunger 68 abuts the slideable piston 70 located in the bore 71 urged to the right by the spring 72. As shown, the piston 70 has a conical recess at 74 to receive a conical headed abutment 76 threaded upon the end 78 of the rod 80. A thumb screw 82 acts as a set screw between the abutment 76 and end 78, as well as a means for withdrawing the rod 80 to the left against the tension of the spring 72. To this end, the screw 82 extends through an L-shaped slot having an axially extending leg 84 and a transversely extending leg 86 providing a shoulder 88 back of which the shank of the screw 82 may be carried to lock the rod 80 in a withdrawn position.

The outer end 90 of the rod 80 freely slides in a bushing 92 and is reduced at 94 to carry a hardened end 96 which engages with the crank pin 16 through a central opening 98 in the shoe 22.

In the modification shown in Fig. 3, the plunger 26' is axially adjustable in the back rest 10' and carries a vertically slotted shoe 22'. Supported on the pin 100 is a bell crank lever 102 which swings in the vertical slot of the shoe

22'. The upper end 104 of the lever 102 has a hardened boss 106 adapted to ride upon the surface of the crank pin 16' for the crankshaft 18'. The indicator rod 80' has a reduced end 94' which in its advanced position engages the end 104 of the lever 102 and swings the same to bring the boss 106 into engagement with the pin 16'. When the rod 80' is withdrawn, the lower end 108 of the lever 102 is heavy enough to swing the end 104 counterclockwise back 10 against the shoulder 110 of the vertical slot in the shoe 22'. In this position the boss 106 is out of contact with the pin 16' being ground and only the outer face 112 of the shoe 22' engages the pin 16'.

The present invention is particularly adapted to the regrinding of crankshafts which have been in service. To permit the threaded shaft 48 to be threaded in and out to change the location of the abutment end 50, a knurled nut 114 is fixed thereto. By adjusting the abutment 50, the location of the shoe 22 relative to the pin 16 can be changed. As the housing 60 will rotate with the shaft 48, by having graduations 116 thereon divided into thousandths of an inch, accurate regulations of the location of the abutment 50 can be made. Further, by having the lead of the threads on the shaft 48 and the outer thread on the nut 58 the same, the graduation 116 will also serve to indicate the rate of advancement if adjustment between the housing 60 and the nut 58 is desired to bring the limits of movement of the indicator rod 80 within the limits of the indicator 64 which usually does not exceed .250''. It will be understood that it is only necessary that the end 96 of the indicator rod 80 project a slight distance beyond the outer face 118 of the shoe 22 in order to function as a centering and set-up gauge.

To compensate for wear of either the end 96 of the rod 80 or the shoe 22, by loosening the set screw 82 the rod 80 may be screwed into or out of the abutment 76.

In using the above discussed apparatus for centering and set-up in regrinding worn crankshafts, the end 96 of the indicator rod 80 may project as much as .100'' beyond the face 118 of the shoe 22 without any chance of injury to the indicator. By loosening the set screw 62, the housing 60 may be screwed in or out on the nut 58 to provide the right amount of tension on the spring 72 to keep the rod 80 at its end 96 against the crank pin 16.

It is important to note that regardless of the size crank pin being ground that the distance between the face of the shoe 22 and the indicator mechanism never changes except for the wear of the shoe 22 which is extremely slight.

To describe a typical use of the aforesaid apparatus in regrinding a worn crankshaft, starting with the most badly worn crank pin, the same is centered for rotation about its longitudinal axis and with the pin 16 snug against the face 118 of the shoe 22, as well as the shoe 24, the crank pin 16 is ground undersize, for example .020''. The screw 82 is then removed from behind the shoulder 88 to permit the tension of the spring 72 to urge the end 96 of the indicator rod 80 into engagement with the surface of the finished ground pin 16. To simplify the reading of the indicator dial, the screw 62 can be loosened and the housing 60 adjusted so the dial reads zero plus .005'' to .010'' with the end 96 in con-

tact with the finished pin. Locknut 54 is then loosened and the housing 60 and shaft 48 are then rotated in a backing off direction until the dial reads zero minus .010'' or one-half the amount ground off the finished crank pin. This is also the amount of the movement of the abutment 50 and the plunger 26 and shoe 22 will slide inwardly a corresponding amount. The locknut 54 is then tightened. Thereafter the crankshaft carrying fixtures are locked and the chuck loosened just enough to permit the crankshaft to turn in the chuck. The back rest 10 is then loosened by sliding the draw bolt 12 and the back rest is slide axially along the table 14 to the next crank pin 16 to be ground and upon finishing secured to the table 14. The crankshaft 16 is then rotated until the pin 16 to be ground touches the shoe 22. To obtain the final grinding position, the crankshaft is moved away from the shoe 22 until the indicator dial reads zero. The chucks are then tightened, the crankshaft carrying fixtures are unlocked, and the crankshaft is rotated. There is now .005'' to .010'' clearance between the shoe 22 and the pin 16 to be ground. This is a safeguard for variation in length of stroke. The crank pin is then centered through use of the indicator and the rod 80 is withdrawn by latching the screw 82 behind the shoulder 88 and the bearing is ready to be reground.

Having thus described my invention, what I desire to cover by Letters Patent and claim is:

1. A combination steady rest and indicator for grinders and the like comprising a shoe engaging with and giving support to the work, an indicator rod extending through said shoe, an indicator connected to said rod at a point remote from said shoe, and means to withdraw and hold said indicator rod in an inoperative position.

2. A combination steady rest and indicator comprising a main supporting structure, a plunger slidably supported in said structure for axial adjusting movement, a shoe supported from the outer end of said plunger, a shaft adjustable in said structure and disposed in axial alignment with said plunger, said plunger abutting one end of said shaft whereby said shaft constitutes an adjustable abutment limiting the axial movement of said plunger, an indicator supported on said shaft, an indicator rod extending through said shaft and plunger to a point adjacent the outer face of said shoe, an indicator supported on the end of said shaft remote from opposite said abutment end, and an operative connection between said indicator rod and said indicator.

3. In a crankshaft grinding machine, a combination steady rest and centering and set-up gauge comprising a main structure adapted to be adjusted axially of the crankshaft to back up the crank pins while being ground, structure for steadyng the crankshaft being ground comprising a shoe against which the crank pin bears, means supported in said structure for axial adjustment toward and from the crank pin and carrying said shoe on its outer end, an indicator, means for supporting said indicator in fixed relationship to said shoe in all positions of axial adjustment of said shoe with reference to said crank pin, and an indicator rod extending from said shoe to said indicator, said rod having an end portion adapted to engage said pin to facilitate centering and setting-up of the crank pin 75 for grinding.

4. A combination steady rest and indicator for grinders and the like, comprising a shoe engaging with and giving support to the work, a slot in said shoe, a member pivoted on said shoe to move relative to said shoe in said slot, an indicator rod engaging with the back side of said member to project said member toward the work, and an indicator connected with said rod at a point remote from said shoe.
